(57) **CLAIM**

The ornamental design for portions of side shelves and cabinet drawer, as shown and described.

DESCRIPTION

FIG. 1 is an isometric view of portions of side shelves and cabinet drawer in accordance with the invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines form no part of the claimed design. Surfaces not shown in the drawing are flat, plain and unornamented.

Where rounded broken-line edges are shown at the corners of the shelves/drawers, it is understood that these broken lines represent the bounds of the claimed design.
